(57) **CLAIM**

The ornamental design for an electric muscle stimulation suit, as shown and described.

DESCRIPTION

FIG. 1 is a front view of an electric muscle stimulation suit, showing my new design;

FIG. 2 is a front, right side perspective view of the electric muscle stimulation suit;

FIG. 3 is a right side view of the electric muscle stimulation suit;

FIG. 4 is a back view of the electric muscle stimulation suit;

FIG. 5 is a back, left side perspective view of the electric muscle stimulation suit; the back, right side perspective view being a mirror image thereof;

FIG. 6 is a left side view of the electric muscle stimulation suit; and,

FIG. 7 is front, left side perspective view of the electric muscle stimulation suit.

The broken line showing of the person depicts environment and forms no part of the claimed design.

The masked areas adjacent to the dash-dot broken lines in the figures form no part of the claimed design. The dash-dot broken lines define the bounds of the claimed design and form no part thereof.

The shorter dash-dash broken lines at the seams of the electric muscle stimulation suit illustrate stitching that forms no part of the claimed design.
